UNITED STATES PATENT OFFICE.

JOHN A. BERGAN, OF HOLDEN, MASSACHUSETTS, ASSIGNOR TO JAMES H. WILLIAMS, OF UTICA, NEW YORK.

LOOM-SHUTTLE.

SPECIFICATION forming part of Letters Patent No. 350,341, dated October 5, 1886.

Application filed August 16, 1886. Serial No. 211,045. (No model.)

To all whom it may concern:

Be it known that I, JOHN A. BERGAN, a citizen of the United States, residing at Holden, in the county of Worcester and State of Massachusetts, have invented certain new and useful Improvements in Loom-Shuttles, of which the following, together with the accompanying drawings, is a specification sufficiently full, clear, and exact to enable persons skilled in the art to which this invention appertains to make and use the same.

The object of my present invention is to provide an efficient and serviceable catch mechanism, and to render the shuttle convenient and desirable for manufacture and use.

To this end my invention consists in a shuttle the mechanism of which is constructed as herein shown and described.

In the drawings, Figure 1 is a bottom view 20 of the shuttle. Fig. 2 is a longitudinal central section. Fig. 3 is a longitudinal section of one end of the body. Fig. 4 is a transverse section at the position of line $x-x$ in Fig. 2. Figs. 5 and 6 show the form of the latch, and 25 Figs. 7 and 8 show the form of the spindle-head.

Referring to parts, B denotes the body or shuttle-frame; C, the catch; D, the spindle; E, the fulerum or pivot; F, the spring by 30 means of which the spindle is held in positions of adjustment, and I the bobbin. The spindle D is pivoted on the fulerum-pin E, which passes through the spindle-head D', in the usual manner, and the spring F is seated in a 35 recess formed in the body B, and is provided with a rounded bearing piece, f, that fits into a semi-cylindrical cavity, f', in the spindle-head D', as shown, said spring being arranged to act in the manner substantially as heretofore employed, for sustaining the spindle either 40 at outward or inward position of adjustment.

The spindle-head is provided with a downwardly and backwardly projecting ear or tongue, d, and also with a transverse lug or 45 downwardly-projecting stop, d', disposed on the head at the positions indicated. The catch C is made, as shown in Figs. 5 and 6, with a transverse flange, c, to engage with the groove in the bobbin-head, a central longi-

tudinal slot, c', with upwardly-projecting ears 50 c' at either side thereof, and with a rounded inwardly-curved rear end or tail, c''. This catch C is pivoted to the spindle-head D by a pin, p, which passes laterally through the ears c', and the projection or tongue d, which 55 extends into the slot c' between said ears, so that the catch follows the action of the spindle-tongue d as the spindle is swung up and down. The body B is provided with a cavity for the reception of the spindle-head and catch C, 60 and backwardly-extending grooves b are formed in the sides thereof, into which the tail of the catch is introduced and therein retained by the overhanging lips or flanges at m, the tail of the catch being free to slide back and 65 forth longitudinally in the groove, but confined against swinging outward or inward. When the end of the spindle is raised from the interior of the shuttle-body, the catch is 70 released from the groove in the bobbin-head by being slightly swung outward and drawn forward by the tongue D of the spindle-head in a manner to avoid the liability of roughing or splitting up slivers from the bobbin-head— 75 a defect incident to many former styles of shuttle-catches, and a source of much waste and inconvenience. When the spindle is down in place, the lug d' acts as a stop against the inner side of the catch, which latter holds the 80 bobbin securely in place. The action is indicated by dotted lines in Fig. 2. The slot c' in the catch affords convenient facility for oiling the fulerum-pivots and spring-bearings. With the construction shown the necessity of 85 a spring for pressing in the catch is obviated, the spindle-adjustment spring F giving all the power necessary.

What I claim as of my invention, and desire to secure by Letters Patent, is—

1. The combination of the shuttle-body provided with the grooves b, the spindle having the tongue d on its head, and the slotted catch C, pivoted to said tongue at p, with its tail fitted to slide in the groove b and confined therein by overhanging lips, substantially as shown 95 and described.

2. The combination of the body B, having the grooves b, the spindle D, having the head

D', fitted with the recess *f'*, rearwardly and downwardly projecting tongue *d*, and downwardly-projecting lug *d'*, the catch C, having the flange *c*, central slot, *c'*, and ears *c''*, pivoted to said tongue at *p*, with its tail confined in said groove, the fulcrum-pin, and spring F, with the bearing-piece *f*, engaging the recess *f'* on the spindle-head, as shown, and hereinbefore described.

Witness my hand this 5th day of August, 1886.

JOHN A. BERGAN.
